UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE-EXCHANGE SYSTEM.

1,304,335.

Specification of Letters Patent. Patented May 20, 1919.

Application filed October 26, 1916, Serial No. 127,946. Renewed March 6, 1919. Serial No. 281,070.

To all whom it may concern:

Be it known that I, ALBEN E. LUNDELL, a citizen of the United States, residing at New York, in the county of Bronx and State 5 of New York, have invented certain new and useful Improvements in Automatic Telephone-Exchange Systems, of which the following is a full, clear, concise, and exact description.

10 This invention relates to telephone exchange systems, and more particularly to improvements in automatic or semi-automatic telephone exchanges.

It is the object of this invention to provide a new and improved arrangement for private branch telephone exchanges, that is to say, for telephone exchanges in which a connector switch is adapted to seize an idle one of a plurality of lines leading to a 20 private telephone exchange.

As well known, in private branch telephone exchanges, a plurality of lines are identified by one and the same number in the telephone directory. The connector 25 switch which is set in accordance with this numerical designation of the called line, will be stepped on to a set of terminals characterized by the called line's numerical designation, and if the line terminating in 30 these contacts is busy, the connector will automatically hunt for an idle line leading to the private telephone exchange. If all the lines leading to this exchange test busy, a signal will be conveyed to the calling party 35 and the release of the connector and other apparatus employed in the building up of the connection follows.

Private branch telephone exchanges are usually employed by larger business concerns where, after office hours, the private 40 exchange is closed for traffic. It may happen, however, that it is desired to provide facilities for outside connections for one station, which may be either an operator's position or a telephone substation. During office hours, connection may be had 45 to this telephone station by asking for it from the operator whose position is reached by the connector. After office hours, however, the private branch exchange is closed, and no attempt will be made to seize the 50 private telephone exchange.

The present invention provides means whereby a specially designated private 55 branch station may be reached by direct

means, that is to say, without regard to this, that it forms a part of a private branch exchange. This is accomplished by making possible the testing of a line leading to this special station, either as one of the private 60 branch exchange lines, or as a regular direct telephone line.

The drawings diagrammatically represent a semi-automatic telephone exchange system embodying the present invention. Figure 2 65 should be placed to the right of Fig. 1.

A selector switch 100, shown in Fig. 1, and a connector switch 200, shown in Fig. 2 are of the so-called panel type, fully disclosed in Patent No. 1,123,696 to E. B. Craft 70 and J. N. Reynolds. A sequence switch 101, shown in Fig. 1, is adapted to control connector switch 200 by various contacts, indicated at the right-hand side of the vertical dotted line in Fig. 1. This sequence switch 75 may be of a similar structure as the one shown in a Patent No. 1,127,808 to J. N. Reynolds and C. F. Baldwin. Within a dotted rectangle in Fig. 1 a sender is shown. A full disclosure of the circuits and controlling apparatus of such sender may be had from my Patent No. 1,168,319. In the drawing, only an upper zero counting relay 102 and a stepping relay 103 of such sender are indicated, and the description 80 refers only in general terms to the operation thereof. A contact 104, shown within the dotted rectangle, is controlled by a sequence switch (not shown) associated with the sender, which is in turn controlled through 85 the front contact and armature of relay 102. 90

There are sequence switch contacts shown at the left-hand side of the dotted line in Fig. 1. These contacts, with the exception of contact 104, are controlled by a sequence 95 switch (not shown) associated with selector 100. This sequence switch, while moving from position 1 to position 13, controls the circuits of selector 100. The detail operation of such selector switch is disclosed 100 in the mentioned Patent No. 1,168,319.

A subscriber at station 105, desiring to obtain a connection, removes his receiver from the switchhook, whereupon a line relay 106 causes the lighting of a lamp 107. The operator, noticing this lamp lighted, inserts plug 108 into an answering jack 109 of the calling line, whereupon relays 110 and 111 become energized. Relay 110 disconnects the line relay 106 and thus causes 110

- the extinguishing of lamp 107. A calling supervisory relay 112 also becomes actuated. Relay 111 starts the sequence switch, the contacts of which are indicated at the 5 left-hand side of the dotted line of Fig. 1. Under the control of this sequence switch, the sender is associated with the selector 100, and in accordance with the adjustment of this sender, the selector 100 is set.
- 10 After the setting of selector 100 onto trunk terminals 113, 114 and 115, the associated sequence switch is standing in position 7, into which position it was moved by means including relay 116 operated during 15 the setting of the selector. A circuit is closed from grounded battery, through the winding of a relay 116, sequence switch contacts 117 and 118, the contact 104 of the sender sequence switch, resistance 119, the 20 windings of the stepping relay 103, back contact and the armature of the counting relay 102, to ground. Relay 116, upon energization, moves the selector sequence switch into position 8 and establishes a locking circuit for itself through its right-hand armature and 25 front contact, and sequence switch contact 120, to ground at the armature of relay 102. A circuit is established from plus battery through the left-hand armature and 30 front contact of relay 116, sequence switch contact 121, selector wiper 122, terminal 113, a sequence switch contact 123, a conductor 124, and the windings of a relay 125, to minus battery. Relay 125 becomes energized and closes a circuit from plus battery, through its left-hand armature, sequence switch contacts 126 and 127, and the winding of a relay 128 to minus battery. 35 Relay 128, by attracting its right-hand armature, closes a locking circuit for itself through terminal 115, wiper 129, to the plus pole of the battery at selector 100. Relay 128 also closes a circuit from plus battery through its left-hand armature and front 40 contact, a contact 130, and the power magnet of sequence switch 101, to the minus pole of battery for moving this sequence switch out of position 1. Under the control of its normal spring 131, the sequence switch 45 is moved into position 2. When the sequence switch 101 moves out of position 1 and opens contact 123, relay 125 remains energized by a circuit closed from grounded battery, through its windings, conductor 124, sequence switch contacts 132 and 133, the 50 right-hand front contact and armature of relay 125, a conductor 134, a sequence switch contact 135, and through the selector 100 to ground at relay 116.
- 55 In position 2 of sequence switch 101, a circuit is established from grounded battery, through the winding of a magnet 201, a conductor 202, sequence switch contacts 136 and 133, the right-hand front contact and armature of 60 relay 125, conductor 134 and sequence switch contact 135 to ground through the left-hand armature and front contact of relay 116. This magnet 201, by attracting its armature, presses a brush rod 203 of the connector 200 against a roller 204, 70 constantly rotating in the direction indicated by the arrow. The brush rod carries wipers 205, 206 and 207 and commutator brushes 208 and 209 in an upward direction. The wipers are adapted to engage the terminals of a contact bank 211. By means of a cam 206', the wipers are normally held apart and out of alignment with the terminals of bank 211. Commutator segments 213 and 214, provided on a plate 212, may 80 be engaged by brushes 208 and 209 respectively.

As soon as the brush 209 engages the segment 214, ground is connected through a conductor 216, a sequence switch contact 85 137, conductor 138, a sequence switch contact 139, terminal 114, selector wiper 140, sequence switch contacts 141 and 120, and the right-hand armature, front contact and winding of relay 116 to grounded battery. 90 Due to the closure of this (shunt) path, the relay 103, which was energized by the above traced circuit including relay 116, becomes deenergized.

Supposing that the sender is adjusted to 95 control the sending of one impulse, the stepping relay 103, upon deenergization, causes the actuation of relay 102. This relay, by closing its front contact, causes the sender sequence switch to open contact 104 for a 100 certain time interval, and opens at its back contact the locking circuit of relay 116. As long as brush 209 engages the conducting part of segment 214, relay 116 is maintained energized by current flowing in the above 105 traced shunt path. As soon, however, as brush 209 engages the first insulated portion 214' of the commutator segment, relay 116 becomes deenergized, moves the selector sequence switch into position 9 and opens 110 at its left-hand contact the circuits of relay 125 and magnet 201. Relay 125 closes a circuit from the plus pole of battery, through its left-hand armature and back contact, contacts 142 and 143 and the power magnet 115 of sequence switch 101, to the minus pole of battery. This sequence switch is moved into position 3. Due to the deenergization of magnet 201, the connector is arrested in its upward travel. A circuit is now closed 120 from the plus pole of battery, through a sequence switch contact 144, a conductor 217 and the winding of a trip magnet 218, to the minus pole of battery. The trip magnet, by attracting its armature, moves a trip 125 finger 219 into the path of a catch 220 which carries the cam 206'.

In response to the opening of contact 104, relay 102 became deenergized, and as soon as contact 104 is again closed, the originally 130

traced circuit of relay 116 is reestablished. Relay 116 again locks up, moves the selector sequence switch into position 10 and operates relay 125. Relay 125 locks up its winding and closes a circuit through its left-hand front contact and armature, and sequence switch contacts 126 and 143, for moving sequence switch 101 out of position 3 and into position 4. Contact 136

5

10 is again closed and magnet 201 is thus again operated for causing the further travel of the connector switch.

When catch 220 engages the trip finger 219, the cam 206' is removed from between the connector wipers and these wipers are permitted to move into alignment with the terminals of bank 211. Brush 208 has traveled now far enough to engage a conducting part of commutator segment 213, and

15

20 connects ground through conductor 221, sequence switch contacts 145 and 139, to the winding of relay 116. Relay 103 is then shunted out and causes the energization of the counting relay, predetermined by the adjustment of the sender. When brush 208

25

engages an insulated segment 213', relay 103 becomes again energized.

The connector continues to move in an upward direction until the upper zero counting relay 102 becomes energized. Relay 116 becomes then deenergized and moves the selector sequence switch into position 11, and by opening the circuit of relay 125, causes sequence switch 101 to move into position 5. Magnets 218 and 201 become deenergized and the latter causes the arresting of the connector.

Upon the reestablishment of the circuit of relay 116, the last or units selection follows. Relay 116 locks up its winding, moves the selector sequence switch into position 12, and causes the operation of relay 125, which also locks up its winding and moves sequence switch 101 into position 6. In this position of the sequence switch, a magnet 222 is connected in circuit from grounded battery, through the winding of this magnet, conductor 223, sequence switch contacts 146 and 133, the

40

45

50

right-hand front contact and armature of relay 125, 134, 135, 113, 122, 121, and the left-hand front contact and armature of relay 116 to ground. Magnet 222 presses the brush rod against a roller 222' and causes

55 the movement of the connector in an upward direction at a lower speed than roller 204. The shunting of the stepping relay 103 is now again controlled by brush 209, connecting ground through conductor 216 and sequence switch contact 137 to the winding of relay 116.

60

Supposing that the sender is adjusted to cause the connector with its wipers to engage the terminals 224, 225 and 226 from

65

which a line leads to an answering jack 231

in front of a private branch exchange operator. After the connector has sent back to the sender the proper number of units impulses, relay 116 becomes deenergized, causing the movement of the selector sequence switch into position 13 and the deenergization of relay 125, whereupon sequence switch 101 moves into position 8.

A circuit is now closed from ground, through the high-resistance left-hand winding of a test relay 148, sequence switch contacts 147, the low-resistance right-hand winding of the test relay, sequence switch contact 149, conductor 227, wiper 207, terminal 226, and the winding of a relay 228, to the plus pole of grounded battery. The relay 148 is marginal in its operation and will not pull up unless full battery potential is applied through a resistance of 100 ohms to the test terminal 226. The winding of relay 228 is of a resistance of 100 ohms, and therefore in the present case relay 148 becomes energized and closes a circuit from the plus pole of battery, through its left-hand armature and front contact, a contact 150 and the power magnet of sequence switch 101, to the minus pole of battery. The sequence switch is moved into position 10. By attracting its right-hand armature relay 148 shunts out its high-resistance left-hand winding and locks up through its low-resistance right-hand winding in series with relay 228. Relay 228, which does not become energized in series with both windings of the test relay, now becomes energized.

70

75

80

85

90

95

100

105

Other connectors attempting to seize these terminals will connect through their test brush, corresponding to 207, a reduced battery potential to their test relays, whereby the energization of such test relays is prevented.

110

When the sequence switch 101 passes through position 9, a circuit is closed from ground, through sequence switch contacts 151 and 152, and the right-hand winding of a differentially wound relay 153, to the plus pole of grounded battery. The circuit of the left-hand winding of relay 153 being open in the right-hand back contact of relay 148, only one winding (the right-hand winding) of relay 153 is energized, and therefore this relay attracts its armature. The purpose of relay 153 will appear from the further description of the system.

When sequence switch 101 reaches position 10, relay 125 being deenergized, a circuit is closed from the plus pole of battery, through the left-hand armature and back contact of relay 125, contacts 142 and 143, and the power magnet of sequence switch 101, to the minus pole of battery, and this sequence switch is moved out of position 10 and into position 14. In position 14 of the sequence switch 101, the circuit through the left-hand armature of relay 148, se-

120

125

130

quence switch contact 150 and the magnet of sequence switch 101 is again closed, and thus the sequence switch is moved into position 16, which is the talking position. The 5 private branch exchange operator is now signaled in any well-known manner, for instance, by sending alternating current through the winding of a relay 251, controlling a drop signal 252. The private 10 branch exchange operator establishes the desired connection, e. g., to station 245, by means of her cord circuit 253 in the well-known manner.

If the line terminating in contacts 224, 15 225 and 226 is busy, then the test relay 148 does not become energized. The potential on test terminal 226 may be lowered in the above described manner by including relay 228 in a circuit through a similar test terminal 20 of another connector, or in a circuit extending through the sleeve contact of a jack 231 (similar to jack 109), at the connecting operator's board. As will be hereinafter set forth, the potential on the terminal 226 25 may be lowered also by causing a relay 230 to pull up its outer armature.

In position 8 of the sequence switch 101, a circuit is closed from the plus pole of battery, through the left-hand armature and 30 back contact of relay 148, the back contact and armature of relay 153, sequence switch contact 154, conductor 138, sequence switch contact 155, conductor 124, and the windings of relay 125, to the minus pole of battery. 35 Relay 125, by attracting its left-hand armature, causes the movement of sequence switch 101 out of position 8 and into position 10. In position 10 of the sequence switch, a circuit is closed from grounded 40 battery, through the winding of magnet 222, conductor 223, sequence switch contacts 146 and 133, the right-hand armature and front contact of relay 125, conductor 134, and a sequence switch contact 156, to ground. 45 Magnet 222 thus again becomes energized and causes the further travel of the connector switch. As long as brush 207 passes over terminals like 226, an energizing circuit is maintained from ground, through the 50 right-hand armature and back contact of relay 148, the left-hand winding of relay 153, sequence switch contact 157, conductor 227, wiper 207, terminal 226, and the winding of a relay like 228, to the plus pole of 55 grounded battery. In view of the fact that in position 10 of the sequence switch the right-hand winding of relay 153 is also energized, this relay does not pull up its armature. As soon as the test wiper 207 engages 60 a terminal 226, on which full battery potential exists, relay 148 becomes energized. Relay 148 opens at its left-hand back contact the circuit of relay 125, and at its right-hand back contact, the circuit including the 65 left-hand winding of relay 153. Relays 153

and 125 become deenergized, and the latter causes sequence switch 101 to move out of position 10 and into position 14, from which position it is moved into position 16 by a circuit closed at the left-hand front contact 70 of relay 148, as previously described.

Supposing that all the lines leading to this private branch exchange are busy, that is to say, the test contacts individual to such lines are connected through a relay like 228 75 to the positive pole of battery, the potential of which has been reduced. The test terminal 260 of the last private branch exchange line is connected through a 100-ohm resistance 261, which in practice may comprise a resistance like 229 and a relay like 230, to the minus pole of grounded battery. When wiper 207 engages this terminal, the current flowing through the left-hand winding of relay 153 is not of the proper direction to maintain it energized. This relay, therefore, under the control of its right-hand winding, pulls up its armature under the control of its right-hand winding, and by opening the circuit of relay 125, causes 80 the movement of sequence switch 101 out of position 10 and into position 14. If full battery potential exists on terminal 260, then the line is seized in the same manner as above described. If, however, the potential 85 on this terminal is reduced, relay 148 does not become energized, and therefore sequence switch 101 will stay in position 14. As soon as the sequence switch leaves position 10, the circuit through the right-hand 90 winding of relay 153 is opened, and this relay becomes deenergized. If, as in the present case, the sequence switch 101 rests in position 14, a circuit is closed from the minus pole of battery, through the winding 95 of a magnet 231, conductor 232, sequence switch contacts 160, the left-hand back contact and armature of relay 148, to the plus pole of battery. Magnet 231 presses the brush rod against a roller 233, constantly 100 rotating in the direction indicated by the arrow, whereby the connector is restored to its normal position. As soon as the connector reaches the normal position, a circuit is closed from ground through the 105 brush 208, a conducting segment 234, conductor 235, a contact 165 and the power magnet of sequence switch 101, to grounded battery, whereby this sequence switch is moved through position 16 into position 17. 110 In position 17 a circuit is closed from ground through the secondary winding of an induction coil 161, sequence switch contacts 162, conductor 163, and through terminal 114 and wiper 140 to the connecting 115 operator's telephone set (not shown). A busy tone apparatus is inductively connected to this secondary winding 161, and therefore the connecting operator will be informed that the line is busy. She then 120 125 130

- causes the release of selector 100 by any well-known means. As soon as the wiper 129 leaves terminal 115, the locking circuit of relay 128 is opened. This relay, upon de- 5 energization, closes a circuit from the plus pole of battery, through its left-hand armature and back contact, a contact 164, and the power magnet of sequence switch 101 to the minus pole of battery. This causes 10 the movement of the sequence switch out of position 17 and into position 18, whereupon the above described circuit through brush 208 is again closed and sequence switch 101 is moved out of position 18 into its normal 15 position.
- If, after the successful establishment of a connection, the subscribers desire disconnection, then by hanging up their receivers they may cause the deenergization of supervisory relays 112 and 166. The connecting operator, noticing the clearing-out signal, causes the release of selector 100, whereupon relay 128 becomes deenergized and closes through its left-hand armature and back 20 contact a circuit for moving sequence switch 101 out of position 16 and through position 17 into position 18. A circuit is then closed for the release magnet 231 from the plus pole of battery, through sequence switch 25 contacts 167 and 168, and when brush 208 engages conducting segment 234, the selector 101 is moved out of position 18 into position 1, opening thus the circuit of the release magnet 231.
- If it is desired to make possible the direct seizure of a private branch exchange line, such as the line leading to station 245, then this subscriber's station is connected by means of the private branch exchange operator's cord circuit 253 to a trunk leading to 30 some other connector terminal than a private branch exchange terminal, *e. g.*, terminals 224' and 225'.
- The connector 200, when operated in accordance with any number designating a private branch exchange, seizes the line designated, if such line is idle. If, however, the designated line is busy, the connector automatically hunts for an idle line leading 40 to the private exchange. As shown in Fig. 2, the private branch exchange line terminating in contacts 224, 225 and 226 and multiples thereof, is multiplied to connector terminals 224', 225' and 226'. The connecting 50 operator may adjust her sender to control the setting of the connector on to the terminals 224', 225' and 226' of this line. If the terminal 226' tests idle, then relay 148 becomes energized, the circuit being closed from 55 grounded battery through the winding of a 10-ohm relay 230, a 90-ohm resistance 229, terminal 226', and then through the windings of relay 148 to ground. This relay controls the connector in the same manner 60 as above described. Relay 230 becomes en- ergized and connects ground through a 50-ohm resistance 240, and the winding of the 100-ohm relay 228, to the plus pole of grounded battery. Relay 228 becomes energized and the potential on test terminal 226 70 is reduced. The line leading to station 245 tests busy at the multiples of terminal 226, and at the sleeve contact of jack 281. Another connector attempting to seize the line leading to station 245 through terminals 75 224', 225', 226', will be rejected because of the low-resistance path closed to test terminal 226' through the low-resistance right-hand winding of test relay 148.
- In order to prevent the actuation of relay 230, in response to the energization of relay 228, the relay 228 closes at its inner front contact a short circuit around the winding of relay 230.
- It will be noted that if the line terminating in jack 250 is seized through the branch leading to terminals 224, 225 and 226, the relay 228 is actuated, and if this line is seized through the branch leading to terminals 224', 225' and 226', the relay 230 is actuated. 85 Relays 228 and 230 are individual to the line, and serve to cut off the line relay 241 if the line is seized as a calling or called line. If the inner front contact of cutoff relay 228 was not connected to the winding of cutoff 90 relay 230, then, upon the energization of the former relay, a circuit would be established from ground through the outer armature and back contact of relay 230, the outer armature and front contact of relay 228, resistances 243 and 249 and the winding of relay 230 to grounded battery. This energizing circuit being controlled at the back contact of relay 230 would cause the latter 95 to "buzz" and would render impossible the 100 testing of the line at 226.
- If it is desired to initiate a call from station 245, then, by removing the receiver from the switchhook at that station, relay 270 becomes energized and actuates a signal 271 110 at the private operator's position, who then, by means of her cord circuit 253, establishes the desired connection.
- If the station 245 is permanently connected for outside connections in the above 115 described manner, then upon the removal of the receiver, a circuit is established from grounded battery, through the inner armature and back contact of cutoff relay 230, the inner armature and back contact of cutoff relay 228, the winding of a line relay 241, the apparatus at station 245, the outer back contact and armature of relay 228, and the outer back contact and armature of relay 230, to ground. Relay 241 closes a circuit 120 from ground through its front contact and armature, and a lamp 242, to grounded battery, for attracting the connecting operator's attention. When this operator inserts a plug such as 108 in the answering jack 231 125 130

of station 245, relay 228 becomes energized, opens the circuit of relay 241, and thus causes the extinguishing of lamp 242. A circuit is also closed from ground through 5 the outer armature and back contact of relay 230, the outer armature and front contact of relay 228, and a 50-ohm resistance 243, to the test terminal 226', thus preventing the seizure of station 245 through that test terminal. 10 If an attempt is made to seize the line leading to this station 245 through terminals 224, 225, 226, then it will be seen that due to the circuit closed for relay 228 through the sleeve contact of jack 231, the 15 potential on this terminal is also reduced, and, therefore, the test relay of the connector cannot become energized.

What is claimed is:

1. In a telephone exchange system, a plurality of lines, means for rendering any one 20 of said lines busy, a switching device operable to engage any one of said lines when idle, automatic means operative upon the engagement of a busy line by said device for 25 causing it to successively engage the other lines, releasing means for said device operated upon the engagement of the last line if such line is busy, and means operative upon the engagement of a certain one of said lines 30 for preventing the operation of said automatic means.

2. In a telephone exchange system, a plurality of lines, means for rendering any one 35 of said lines busy, a selectively operable switching device, means for operating said switching device to engage one of said lines, automatic means operative thereupon if said line is busy for causing said switching device to successively engage the other lines, 40 a releasing means for said switching device operated thereupon if the last one of said lines is busy, and means for operating said releasing means upon the engagement by said device of another line than the last line 45 if such line is busy.

3. In a telephone exchange system, a line, a plurality of test contacts therefor, means for causing said line to test busy at all of 50 said test contacts, a selectively operable switching device, means for causing it to engage any one of said test contacts, a normally inactive releasing means for said device operated in response to the engagement of one of said busy test contacts by the device, and means for maintaining said releasing means in its normal condition if said device engages another one of said busy test contacts.

4. In a telephone exchange system, a selectively operable switching device, a line, 60 a plurality of contacts for said line, a series of other contacts, said contacts being arranged for engagement by said switching

device, means for placing a busy test potential upon any one of said contacts, means for 65 causing said switching device to engage one of the contacts of said line, automatic means operative if said last-mentioned contact tests busy for causing said switching device to successively engage said series of other contacts, a releasing means for said device operated upon the engagement of the last contact in the series if such contact tests busy, and means for operating said releasing means in response to the engagement of another contact of said line if such contact 70 tests busy. 75

5. In a telephone exchange system, a plurality of lines, two calling test terminals for one of said lines, one calling test terminal for each one of the other lines, a selectively operable switching device, means for rendering any one of said lines busy, means for operating said device to test said one of said lines at one of its test terminals, means operative thereupon and controlled by the busy condition of said line for causing said device to test said other lines at their terminals until an idle one is found, releasing means for said switching device operated if all 80 said other lines test busy, means for causing said switching device to test said one of said lines at the other of its test terminals, and means operative thereupon if said line is 85 busy for actuating said releasing means. 90

6. In a telephone exchange system, a line, two test contacts for said line, two relays, one connected to each one of said test contacts, and means controlled by one of said relays for preventing the other relay from operating. 100

7. In a telephone exchange system, a line, a plurality of branches therefor, a switching device for seizing said line through any one of said branches, two cutoff relays for said line, means for actuating one of said relays upon the seizure of the line through one branch and the other relay upon the seizure of the line through another branch, and means operative upon the actuation of one 105 of said relays for preventing the other one from operating. 110

8. In a telephone exchange system, a connector switch, a plurality of private branch exchange lines terminating at said connector switch, means operable at will for controlling said switch to select one of said lines, automatic means operable thereupon for causing said switch to seize any one of said lines, and means operable at will for causing said switch to select and seize a certain one 115 of said lines. 120

In witness whereof, I hereunto subscribe my name this 17th day of October A. D., 1916.

ALBEN E. LUNDELL.
